US0D1071637S

(12) United States Design Patent (10) Patent No.: US D1,071,637 S
(45) Date of Patent: * Apr. 22, 2025

(54) STAND FOR WINE BOXES

(71) Applicant: Mohamed Khemaissa, La Roque-d'Anthéron (FR)

(72) Inventor: Mohamed Khemaissa, La Roque-d'Anthéron (FR)

() Term: 15 Years

(21) Appl. No.: 35/519,023

(22) Filed: Sep. 8, 2023

(80) Hague Agreement Data

Int. Filing Date: Sep. 8, 2023

Int. Reg. No.: DM/232909

Int. Reg. Date: Sep. 8, 2023

Int. Reg. Pub. Date: Nov. 17, 2023

(30) Foreign Application Priority Data

Jun. 8, 2023 (FR) 20232632-001
